PROCESS FOR THE DECORATION OF
CERAMICS

Ernest Robert Box and Frank Enoch Kerridge,

they & Company Limited, London, England, a
British company

No Drawing. Application November 30, 1943, Se-
rial No. 512,354. In Great Britain December 9,
1942

5 Claims. (Cl. 41—33)

1

This invention relates to the production of transfer paper suitable for printing ceramic or other transfers. Such transfer paper usually consists of a sheet of porous gummed backing paper to the gummed side of which there is applied a transparent film of cellulose acetate, cellulose nitrate or the like which may also contain a plasticiser. To obtain the optimum result it is essential that the said film should have a uniform predetermined thickness. The film material, such as cellulose nitrate or cellulose acetate, is usually applied to the gummed backing paper in the form of a solution, for example in acetone, by means of a coating machine and a uniform predetermined thickness is secured by regulating the viscosity of the solution and by making mechanical adjustments in the coating machine. Since the paper is white and the plastic film is transparent, it is impossible to observe any differences in film thickness by visual inspection and the machinery must therefore be stopped from time to time to determine the film thickness by actual measurement. It is still possible, however, for local differences in film thickness to occur.

According to the present invention these difficulties are overcome by using for the preparation of the film on a transfer paper a coating solution comprising a transparent colouring material which is soluble in the solvents used. Organic dyes are very suitable and as examples we mention Malachite Green, Rose Bengal and Methyl Violet, all of which are easily soluble in acetone.

Suitable coating solutions are as follows:

(1)

	Parts
Cellulose acetate	10
Diethyl phthalate	3
Acetone	100
Malachite Green	0.01

(2)

	Parts
Cellulose nitrate	10
Acetone	100
Rose Bengal	0.02

(3)

	Parts
Cellulose acetate	10
Diethyl phthalate	3
Acetone	100
Methyl Violet	0.006
Malachite Green	0.004

By the use of a coloured coating solution it is possible to observe by visual inspection any varia-

2

tions in the thickness of the resulting film. Such variations will be revealed by a difference in the colour of the film and adjustments may be made without stopping the coating machinery. Variations in the thickness of the film after drying are shown by irregularities in the depth of the colour and it is therefore possible to cut out and discard those portions of the paper which have an unsatisfactory film, thus effecting an appreciable economy in the number of transfers rejected after the colour design has been printed on the film.

Another advantage of the use of a coloured film is that it is frequently necessary to have a white background colour in the transfer design and any faults in the printing or registration of the white part of the design are much more readily shown up when the design is printed on a coloured background than when it is printed on a white paper coated with a transparent colourless film.

20 While we prefer a bluish-grey tint similar to that given by the mixture (3) above, the colour of the colouring material used in the process according to this invention is not important. The colouring material must, of course, be soluble in the coating solution and also, in the case of ceramic transfers, must burn off during the subsequent firing operation without leaving any residue.

What we claim is:

30 1. A process for the decoration of a ceramic with a design of a material which will not burn on firing, which consists in applying to the gummed side of a gummed backing paper a thin transparent coloured film comprising a water insoluble cellulose ester selected from the group consisting of cellulose nitrate and cellulose acetate, and an organic dye, which film will burn away on firing; applying said design to said film; and transferring said coloured film with the design thereon to a ceramic.

2. A process for the decoration of a ceramic with a design of a material which will not burn on firing, which consists in applying to the gummed side of a gummed backing paper a thin coating of a solution in an organic solvent of a water insoluble cellulose ester selected from the group consisting of cellulose nitrate and cellulose acetate, and an organic dye; allowing the solvent to evaporate to produce on said paper a thin transparent coloured film which will burn away on firing; applying said design to said film; and transferring said film with the design thereon to a ceramic.

3. A process as claimed in claim 1 wherein the organic dye consists of Malachite Green.

4. A process as claimed in claim 1 wherein the organic dye consists of Rose Bengal.

5. A process as claimed in claim 1 wherein the organic dye consists of Methyl Violet.

ERNEST ROBERT BOX.
FRANK ENOCH KERRIDGE.
